UNITED STATES PATENT OFFICE.

ROBERT J. SEATOR, OF BATTLE CREEK, MICHIGAN.

MOTOR.

Application filed June 15, 1922. Serial No. 568,484.

To all whom it may concern:

Be it known that I, ROBERT J. SEATOR, a citizen of the United States, residing at Battle Creek, county of Calhoun, State of Michigan, have invented certain new and useful Improvements in Motors, of which the following is a specification.

This invention relates to improvements in motors.

10 My improved motor is especially designed by me for use in connection with thermostats, or as a thermostat motor, and I have illustrated my improvements in the accompanying drawing as I have embodied them 15 for such use.

The main objects of the invention are:

First, to provide an improved motor of the class described which is practically noiseless in its operation.

20 Second, to provide an improved motor of the class described which is very simple and compact in structure.

Third, to provide an improved motor of the class described which is simple and 25 economical to produce and at the same time very durable and convenient to operate.

Further objects, and objects relating to structural details, will definitely appear from the detailed description to follow.

30 I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a diagrammatic view showing my improved motor in operative relation to the 40 draft members or dampers of a furnace.

Fig. II is a plan view of my improved motor with the housing removed.

Fig. III is a vertical section on a line corresponding to line 3—3 of Figs. I, II and 45 IV.

Fig. IV is a vertical transverse section on a line corresponding to line 4—4 of Figs. II and III.

Fig. V is a detail vertical section on a line 50 corresponding to line 5—5 of Figs. II and IV.

Fig. VI is a detail view partially in section on a line corresponding to line 6—6 of Fig. II, showing details of the ratchet 55 clutch connection for the driving sprocket to the driving shaft.

Fig. VII is a diagrammatic view illustrating the electrical connections of the apparatus.

In the drawing similar reference characters refer to similar parts throughout the several views, and the sectional views are taken looking in the direction of the little arrows at the ends of the section lines.

Referring to the drawing, the furnace, 60 shown conventionally at 1, is provided with a draft damper 2 and a check damper 3. These dampers are connected by the cables 4 and 5 to the arms 6 on the driving shaft 7 of my improved motor, suitable guide 70 pulleys being provided for the cables.

My improved motor comprises a base 8 adapted to be mounted on a bracket 9 or otherwise suitably supported. This base is provided with pedestals or uprights 10 having bearings for the shaft 7, the arms 6 being arranged on the outside of these uprights. The driving sprocket 11 has a ratchet connection to the driving shaft, this connection being preferably a ball clutch in 80 order to avoid the noise which is incident to a pawl and ratchet. The sprocket wheel is provided with a drum 12 embracing the cam member 13 on the shaft, the clutch rollers 14 being arranged between the 85 cammed member and the drum, as shown in Fig. VI, the springs 15 being provided to urge the rollers towards engaging position.

A driving chain 16 is arranged over the sprocket and provided with a power weight 90 17, the weight being secured to one end of the chain, the other end being provided with a ring 18 for convenience in grasping. The operator grasping the ring and pulling on the chain raises the weight. Arranged 95 transversely below the driving shaft is a governor spindle 19 having governor weights 20 mounted thereon by means of the springs 21, one end of the springs being secured to the collar 22 fixed to the shaft. 100

The other end of the springs is secured to the hub 23 of the brake disk 24 so that the brake disk is moved on the shaft by means of the governor weights. The adjustable member 25 is provided to coact with the 105 brake disk 24. The governor spindle 19 is connected to the driving shaft by means of the transmission worm 26 which is disposed vertically at the side of the driving shaft and connected thereto by means of 110 the worm gear 27 on the driving shaft.

The worm 26 has a worm gear 28 connect-

ed thereto and meshing with the worm 29 on the governor spindle. This provides a substantially noiseless driving connection from the driving shaft to the spindle. The 5 driving shaft is controlled by the stop lever 30 pivoted at 31 and coacting with the stop disk 32 on the driving shaft.

A pair of electromagnets 33 are provided and operatively connected to a thermostat, 10 the thermostat and the connections not being shown as they form no part of this invention. The lever 30 is provided with an armature 34 coacting with these electromagnets. The outer end of the lever is extended 15 to coact with a stop 35 carried by the stop ring 36 which frictionally engages the periphery of the brake disk 24. This relieves the governor mechanism of shock when the stop engages the driving shaft.

20 A pair of contacts 37 is provided to coact with the contact pin 38 on the driving shaft, the pin engaging first one and then the other of these contacts and completing the circuit connection through the thermostat 25 when the motor is at rest. The contacts 37 are mounted on an insulating block 39 and connected to the binding posts 40. The contact pin 38 is grounded through the frame. A release rod 41 is provided for releasing 30 the locking lever 30 when it is desired to operate the motor manually as may be desired in starting a fire or adding fuel to the furnace or the like.

The connections for the apparatus to the 35 damper 2 and the check 3 of a furnace are shown in Fig. I. The thermostat by which the device is controlled is not illustrated as such devices are well known on the market and their use well understood.

40 Assuming a variation in temperature such as will actuate the thermostat to close a circuit, the electromagnet is actuated, thereby lifting the control lever or latch 30 from the disk 32. The lever riding on the periphery 45 of the disk drops into the second or opposed notch. The driving means for the shaft 7, including the weight, the sprocket and the worm connections, is controlled by the governor means consisting of a spindle 19, a 50 governor, weights and a friction or brake disk, the spindle 19 being connected to the shaft 7 through the worm gears 26, 27, 28, 29.

55 This results in a substantially noiseless drive and one which is easily controlled. The excess speed will shift the brake disk against the fixed brake member 25 which may be adjusted as desired to check the spindle 19 and the parts attached thereto. 60 A stop 35 having frictioned engagement with the disk is provided.

I have illustrated my improvements in a very practical embodiment or adaptation thereof. I have not attempted to illustrate 65 or describe certain modifications or adapta-

tions which I contemplate, as I believe the disclosure made will enable those skilled in the art to which my invention relates to embody or adapt the same as may be desired.

Having thus described my invention, what 70 I claim as new and desire to secure by Letters Patent, is:

1. The combination of a driving shaft provided with arms adapted for connection to the member to be operated, a governor 75 spindle disposed transversely below said driving shaft, governor weights mounted on said spindle, a brake disk mounted for axial movement on said spindle and operatively associated with said governor weights, an 80 adjustable brake member coacting with said brake disk, a transmission worm having a transmission gear connected thereto, said driving shaft being provided with a worm gear coacting with said transmission worm 85 and said spindle with a worm coacting with said transmission gear, a stop disk on said driving shaft, a pivoted stop lever coacting with said stop disk, an electromagnet, said stop lever being provided with an armature 90 coacting with said electromagnet, a stop ring coacting with said stop lever and frictionally engaging the periphery of said brake disk, a pair of contacts, and a contact pin on said driving shaft adapted to engage with 95 one of said contacts when said stop lever is in engagement with said stop disk.

2. The combination of a driving shaft provided with arms adapted for connection to the member to be operated, a governor 100 spindle disposed transversely below said driving shaft, governor weights mounted on said spindle, a brake disk mounted for axial movement on said spindle and operatively associated with said governor weights, an 105 adjustable brake member coacting with said brake disk, a transmission worm having a transmission gear connected thereto, said driving shaft being provided with a worm gear coacting with said transmission worm 110 and said spindle with a worm coacting with said transmission gear, a stop disk on said driving shaft, a pivoted stop lever coacting with said stop disk, an electromagnet, said stop lever being provided with an armature 115 coacting with said electromagnet, a pair of contacts, and a contact pin on said driving shaft adapted to engage with one of said contacts when said stop lever is in engagement with said stop disk.

3. The combination of a driving shaft provided with arms adapted for connection to the member to be operated, a governor spindle disposed transversely below said driving shaft, governor weights mounted on said spindle, a brake disk mounted for axial movement on said spindle and operatively associated with said governor weights, an 125 adjustable brake member coacting with said brake disk, a transmission worm having a 130

- transmission gear connected thereto, said driving shaft being provided with a worm gear coacting with said transmission worm and said spindle with a worm coacting with 5 said transmission gear, a stop disk on said driving shaft, a pivoted stop lever coacting with said stop disk, and a stop ring coacting with said stop lever and frictionally engaging the periphery of said brake disk. 70
- 10 4. The combination of a driving shaft provided with arms adapted for connection to the member to be operated, a governor spindle disposed transversely below said driving shaft, governor weights mounted on 15 said spindle, a brake disk mounted for axial movement on said spindle, and operatively associated with said governor weights, an adjustable brake member coacting with said brake disk, a transmission worm having a 20 transmission gear connected thereto, said driving shaft being provided with a worm gear coacting with said transmission worm and said spindle with a worm coacting with 25 said transmission gear, a stop disk on said driving shaft, and a pivoted stop lever coacting with said stop disk. 80
5. The combination of a driving shaft provided with arms adapted for connection to the member to be operated, a driving 30 sprocket on said shaft provided with a roller clutch connection thereto, a driving chain coacting with said sprocket and provided with a power weight, a governor spindle disposed transversely below said driving 35 shaft, governor weights mounted on said spindle, a brake disk mounted for axial movement on said spindle and operatively associated with said governor weights, an adjustable brake member coacting with said 40 brake disk, a transmission worm having a transmission gear connected thereto, said driving shaft being provided with a worm gear coacting with said transmission worm and said spindle with a worm coacting with 45 said transmission gear, a stop disk on said driving shaft, and a pivoted stop lever coacting with said stop disk. 90
6. The combination of a driving shaft, a governor including a spindle, a transmission worm having a transmission gear connected thereto, said driving shaft being provided with a worm gear coacting with said transmission worm and said spindle with a worm coacting with said transmission gear, 50 a stop member on said driving shaft, and a pivoted stop lever coacting with said stop member. 95
7. The combination of a driving shaft, a driving sprocket on said shaft provided 55 with a roller clutch connection thereto, a driving chain coacting with said sprocket and provided with a power weight, a governor including a spindle, a transmission worm having a transmission gear connected thereto, said driving shaft being provided 60 with a worm gear coacting with said transmission worm and said spindle with a worm coacting with said transmission gear, a stop member on said driving shaft, a pivoted stop lever coacting with said stop member, and a stop ring coacting with said stop lever and frictionally engaging said brake disk. 100
8. In a structure of the class described, the combination of a driving shaft, a governor spindle, governor weights, a brake disk mounted for axial movement on said spindle and operatively associated with said governor weights, a brake member coacting with 65 said brake disk, a driving connection from said driving shaft to said spindle, a stop member on said driving shaft, a pivoted stop lever coacting with said stop member, an electromagnet, said stop lever being provided with an armature coacting with said electromagnet, a stop coacting with said stop lever and frictionally engaging said brake disk, a pair of contacts, and a contact pin on said driving shaft adapted to engage with one of said contacts when said stop lever is in engagement with said stop disk. 105
9. In a structure of the class described, the combination of a driving shaft, a governor spindle, governor weights, a brake disk mounted for axial movement on said spindle and operatively associated with said governor weights, a brake member coacting with 70 said brake disk, a driving connection from said driving shaft to said spindle, a stop member on said driving shaft, a pivoted stop lever coacting with said stop member, an electromagnet, said stop lever being provided with an armature coacting with said electromagnet, a pair of contacts, and a contact pin on said driving shaft adapted to engage with one of said contacts when said stop lever is in engagement with said stop disk. 110
10. In a structure of the class described, the combination of a driving shaft, a governor spindle, a brake disk mounted for axial movement on said spindle and operatively associated with said governor weights, a brake member coacting with said brake disk, a driving connection from said driving shaft to said spindle, a stop member on said driving shaft, a pivoted stop lever coacting with said stop member, and a stop coacting with said stop lever and frictionally engaging said brake disk. 115
11. In a structure of the class described, the combination of a driving shaft, a governor spindle, governor weights, a brake 120
- 125
- 130

disk mounted for axial movement on said spindle and operatively associated with said governor weights, a brake member coacting with said brake disk, a driving connection from said driving shaft to said spindle, a stop member on said driving shaft, and a pivoted stop lever coacting with said stop member.

12. In a structure of the class described, the combination of a driving shaft, a driving sprocket provided with a ratchet connection to said shaft, a driving chain coacting with said sprocket and provided with a power weight, a governor spindle, governor weights, a brake disk mounted for axial movement on said spindle and operatively associated with said governor weights, a brake member coacting with said brake disk, a driving connection from said driving shaft to said spindle, a stop member on said driving shaft, and a pivoted stop lever coacting with said stop member.

13. In a structure of the class described, the combination of a driving shaft, a driving sprocket provided with a ratchet connection to said driving shaft, a driving

chain coacting with said sprocket and provided with a power weight, a governor operatively associated with said driving shaft and including a governor spindle having a disk thereon, a stop ring frictionally engaging the periphery of said disk, a stop disk on said driving shaft, and a pivoted stop lever coacting with said stop disk and operatively associated with said stop ring.

14. In a structure of the class described, the combination of a driving shaft, a driving sprocket provided with a ratchet connection to said shaft, a driving chain coacting with said sprocket and provided with a power weight, a stop member on said driving shaft, a pivoted stop lever coacting with said stop member, and a governor mechanism operatively associated with said driving shaft and having a stop element with which said stop lever coacts, said governor stop element being independent of said stop member on said driving shaft.

In witness whereof, I have hereunto set my hand and seal.

ROBERT J. SEATOR. [L.S.]
